UNITED STATES PATENT OFFICE

121,666

DESIGN FOR A PUNCHBOARD DISPLAY CABINET

James William Ash, Windsor, Ontario, Canada

Application April 8, 1940, Serial No. 91,535

Term of patent 14 years

To all whom it may concern:

Be it known that I, James William Ash, a citizen of the Dominion of Canada, residing at Windsor, in the county of Essex, in the Province of Ontario, Dominion of Canada, have invented a new, original, and ornamental Design for Punchboard Display Cabinets, of which the following is a specification, reference being had to the accompanying drawing, forming part thereof.

In the drawing:

I claim:

The ornamental design for a punchboard display cabinet, substantially as shown.

JAMES WILLIAM ASH.
